UNITED STATES PATENT OFFICE.

JAMES R. MOFFATT, OF CHICAGO, ILLINOIS, ASSIGNOR TO UNION SPECIAL MACHINERY COMPANY, OF CHICAGO, ILLINOIS, A CORPORATION OF ILLINOIS.

FABRIC-FOLDING GUIDE FOR TRIMMING MECHANISMS FOR SEWING-MACHINES.

1,276,944.

Specification of Letters Patent. Patented Aug. 27, 1918.

Application filed October 7, 1916. Serial No. 124,364.

To all whom it may concern:

Be it known that I, JAMES R. MOFFATT, a citizen of the United States, residing at Chicago, in the county of Cook, State of Illinois, have invented certain new and useful Improvements in Fabric-Folding Guides for Trimming Mechanisms for Sewing-Machines, of which the following is a description, reference being had to the accompanying drawing and to the figures of reference marked thereon.

The invention relates to new and useful improvements in trimming mechanisms for sewing machines, and more particularly to a fabric folding guide for forming a rib or fold in the material in advance of the trimming mechanism whereby said folded rib may be trimmed off for shaping the article.

An object of the invention is to provide a folding guide which is located in advance of the trimming mechanism and which operates to positively fold the fabric and guide the same thus folded to the trimming mechanism so that the folded part is trimmed off.

A further object of the invention is to provide a guide of the above character which may be adjusted at the will of the operator so that the amount of trimmed off material may be varied.

These and other objects will in part be obvious and will in part be hereinafter more fully disclosed.

In the drawings, which show by way of illustration one embodiment of the invention:

Figure 1 is a front elevation of a machine having my improvements applied thereto, the folding guide being in inoperative position;

Fig. 2 is an enlarged end view of the work supporting arm showing the presser foot, the trimming blades and the folding guide, said folding guide being in inoperative position;

Fig. 3 is a plan view of the same;

Fig. 4 is a view similar to Fig. 2, but with parts of the machine in section and the folding guide raised to operative folding position;

Fig. 5 is an end view of the parts shown in Fig. 2;

Fig. 6 is a view, more or less diagrammatic, showing a treadle for controlling the folding guide;

Fig. 7 is a perspective view, showing a section of fabric having a portion trimmed off, the trimming blade, and the joining of the cut edges by the means of stitching; and

Fig. 8 is a detail showing the manner of supporting the fabric as it is fed to the trimming mechanism.

My invention is especially adapted for the shaping of articles which are tubular in form, such as undervests and the like. In carrying out the invention, I utilize a trimming mechanism wherein the movable trimming blade operates horizontally and is adapted to trim a fabric when raised between the trimming blades. This trimming mechanism is located in advance of a stitching mechanism which is adapted to join the abutted edges or slightly overlapped edges after they are trimmed, and thus a section of the material may be cut out of a tubular shaped article and the cut edges brought together and united by a stitching mechanism. The invention is directed particularly to the means for folding the fabric as it is fed to the trimming mechanism.

This is accomplished preferably by a folding finger or guide which raises or bends the fabric into a ridge form in advance of the trimming mechanism. This fold in the fabric then passes between the trimming blades where it is severed. The guide is mounted so that it may be adjusted at the will of the operator, and thus the amount of fold made in the material may be varied.

The guide is normally disposed in inoperative position so that the fabric will pass the trimming mechanism without being trimmed. By gradually raising the guide a slight fold will be made in the fabric, and the trimming will begin. The guide may be raised and the fold increased, if desired, and thus gradually increasing the section of material being cut out. The guide may then be lowered, decreasing the amount cut out, and finally stopping the trimming entirely. Thus a longitudinally tapered strip may be cut out of each side of an undervest and the trimmed edges joined so as to "full fashion" the article.

Referring more in detail to the drawings:—

I have shown my invention applied to a sewing machine having a cylindrical work supporting arm 1 which is carried by a standard 2 mounted on suitable base 3. This standard also carries an overhanging arm 4. At the forward end of the overhanging arm there is a needle supporting gate 5 in which the needle bar 6 reciprocates. The needle bar 6 is moved up and down by a lever 7 which is operated by a pitman 8 coöperating with an eccentric on the main shaft 9. The gate carrying the needle bar 5 may be oscillated through a suitable mechanism so that a zigzag line of stitching is formed. Coöperating with the needle beneath the work support is a looper 10 which engages the needle loop at each descent of the needle and the looper thread connects the stitches beneath the material. This stitching mechanism is of the well-known type and may be used for joining the abutted edges of fabric. It is understood that this stitching mechanism has been shown and described purely for the purpose of illustrating one form of stitching mechanism for joining the abutted or overlapped edges of fabric sections.

The material is fed up the work supporting arm by a feed dog 11. Coöperating with the feed dog 11 is a presser foot 12 carried by a presser bar 13. Mounted on the presser foot is a fixed trimming blade 14 and a movable trimming blade 15. This movable trimming blade 15 is carried by an oscillating arm 16 which is pivoted at 17 to an extension of the presser foot, and said arm is oscillated by a link 18 which coöperates with an eccentric indicated in dotted lines at 19 in Fig. 1 of the drawings. This eccentric is mounted on the main shaft 9. Also mounted on the arm 16 is a strip deflector 20 which deflects the trimmed off strip away from the needle, which is indicated at 21. The needle 21 passes through a needle slot 22 in the presser foot, and, as above noted, said needle is vibrated laterally so as to form a zigzag line of stitching.

The presser foot is cut-away at 27 directly in front of the needle slot and the trimming mechanism so that the fabric passing underneath the presser foot may be folded or bent into rib form with the rib projecting through this slot or cut-away portion 27. The upwardly projecting rib or fold in the fabric may be thus led between the trimming members of the trimming mechanism and severed. In Fig. 7 of the drawings I have shown a section of fabric indicated at F. This may be a section of fabric which is tubular in form, and the tubular formed fabric may be fed up the work supporting arm of the sewing machine. This section of fabric when the point a was reached was bent into rib form, as above described, so that the trimming blades began to cut the section of fabric at this point a, cutting off a section indicated at f. In Fig. 7 of the drawings, the movable trimming blade is indicated at 16. After the section f is cut out of the fabric, the two, severed edges are brought together underneath the presser foot and the needle enters this fabric section f, first on one side of the abutted edges and then on the other side thereof, thus laying the needle thread, indicated at n, back and forth across the meeting edges and thereby joining the same. The needle loops will be joined by the looper thread on the lower face of the fabric so that the abutted edges will be entirely encircled by the needle and looper threads and the cut edges thus firmly joined.

The present invention is directed more particularly to the means for folding or ribbing the fabric in advance of the trimming mechanism. This is accomplished by a folding finger or guide 28. This folding finger or guide 28 is carried by a supporting shank 29. Said shank has two spaced, downwardly projecting parts 30 and 31. The end cap 32 of the cylindrical work supporting arm is formed with a recess 33. The parts 30 and 31 have their edges beveled, as indicated by the dotted line 34 in Fig. 5 of the drawings, and the recess is under-cut so that the shank will slide up and down in the recess in the end cap. The shank is moved up and down by a lever 35 which is pivoted at 36 to a bracket 37. This bracket 37 is secured to the under face of the end cap 32 by suitable screws 38. A spring 39 is secured to the bracket by suitable screws 40. The free end 41 of this spring engages underneath the lever 35 at the right of the pivotal point 36 as viewed in Fig. 4 of the drawings. This spring tends to lift the right hand end of this lever, and this lowers the folding finger or guide 28. The downward movement of this guide or finger 28 is limited by a stop screw 42 which is threaded into the end of the cap 32 and is located between the parts 31 and 30 so that the shank rests on this screw when the folding finger or guide 28 is in this lowered position. When in this position, the folding finger or guide 28 is below the surface of the presser foot and, therefore, said guide or finger is ineffective to fold the material. Said guide or finger 28 extends into the cut-away portion 27 to a point just in advance of the trimming blades.

When said guide or finger is raised, then the fabric will be folded, as shown in Figs. 4 and 8, and the rib or folded portion of the fabric will pass between the trimming blades and be cut-off. The lever 35 may be connected to either a knee shift or treadle. In Fig. 6 of the drawings, the lever is shown as connected to a treadle 43 by means of a 130

flexible connection 44. A spring 45 holds the treadle raised. When the operator depresses the treadle, the lever 35 will be drawn downward, and this will raise the 5 folding finger or guide so that it becomes effective for folding the material into a rib or fold which may be trimmed off. When the operator releases the treadle, then the spring 41 will move the folding finger or 10 guide to inoperative or ineffective position.

From the above, it will be apparent that the treadle may be gradually depressed so as to fold or rib the fabric so that it will be first cut-off to a very slight extent and the 15 amount cut off increased to a desired point, after which it is gradually tapered off and finally the trimming ceases. This may be done at the will of the operator and without stopping the stitching mechanism.

20 It is obvious that minor changes in the details of construction and the arrangement of parts may be made without departing from the spirit of this invention, as set forth in the appended claims.

25 Having thus described the invention, what is claimed as new is:—

1. The combination of a stitching mechanism, a trimming mechanism including a trimming blade moving horizontally in advance of the stitching mechanism, and a 30 folding guide located in advance of the trimming blade for forming a rib or fold in the fabric which is cut-off by the trimming blade.

35 2. The combination of a stitching mechanism, a trimming mechanism including a trimming blade moving horizontally in advance of the stitching mechanism, a folding guide located in advance of the trimming 40 blade for forming a rib or fold in the fabric which is cut-off by the trimming blade, and means whereby said folding guide may be raised or lowered at the will of the operator, without stopping the stitching mechanism.

45 3. The combination of a stitching mechanism, a trimming mechanism including a trimming blade moving horizontally in advance of the stitching mechanism, a folding 50 guide located in advance of the trimming blade for forming a rib or fold in the fabric and directing the same to the trimming blade whereby said rib or fold is cut-off, means for normally holding said folding 55 guide in ineffective position, and means under the control of the operator for raising said folding guide to form the rib or fold.

60 4. The combination of a stitching mechanism, a trimming mechanism including a trimming blade moving horizontally in advance of the stitching mechanism, a folding 65 guide located in advance of the trimming blade for forming a rib or fold in the fabric and directing the same to the trimming

blade whereby said rib or fold is cut off, means for normally holding said folding guide in ineffective position, and means under the control of the operator for raising said folding guide to form the rib or fold, 70 said means being operable without stopping the stitching mechanism.

5. The combination of a work support, a presser foot having a slot or cut-away portion at its forward end, a trimming mechanism including a trimming blade movable horizontally across said cut-away portion or slot in the presser foot, and stitching mechanism adapted to join abutted edges of fabric, a folding guide located in advance 80 of the trimming blade, and means under the control of the operator for raising said folding guide into said cut-away portion of the presser foot for forming a rib or fold in the fabric which is cut-off by the trimming 85 mechanism.

6. The combination of a work support, a presser foot having a slot or cut-away portion at its forward end, a trimming mechanism including a trimming blade movable 90 horizontally across said cut-away portion or slot in the presser foot, stitching mechanism adapted to join abutted edges of fabric, a folding guide located in front of said trimming blade, means for supporting 95 said folding guide whereby it may be moved vertically and into and out of said cut-away portion of the presser foot, and means under the control of the operator for raising and lowering said guide without stopping the 100 stitching mechanism.

7. The combination of a work support, a presser foot having a slot or cut-away portion at its forward end, a trimming mechanism including a trimming blade movable 105 horizontally across said cut-away portion or slot in the presser foot, a stitching mechanism adapted to join abutted edges of fabric, a folding guide located in advance of the trimming blade, a support for said 110 folding guide whereby the same may be moved vertically into and out of said cut-away portion of the presser foot, a lever attached to said support, a spring for moving said lever in one direction, and a 115 treadle for moving said lever in the opposite direction.

8. The combination of a stitching mechanism for joining the abutted edges of fabric sections, a trimming mechanism for trimming a folded portion of the fabric in advance of the stitching mechanism, means for abutting the trimmed edges as they are led to the stitching mechanism, and means under the control of the operator for forming and 120 varying the fold in the fabric which is trimmed by the trimming mechanism.

9. A sewing machine including in combination, a stitching mechanism, a trimming mechanism in advance of the stitching mech- 125

anism including a trimming blade movable horizontally, a cylindrical work support, a presser foot, said presser foot having a cut-away portion leading to the trimming mechanism, a folding guide, a supporting shank for said folding guide, the forward end of said work support having a recess for guiding said shank, a lever for raising and lowering the guide, a stop for limiting the downward movement of the guide, said stop being so positioned that said guide is inef-

fective for folding the material, and means for shifting the lever to raise the guide for folding the fabric and directing said folded portion of the fabric to the trimming mechanism.

In testimony whereof I affix my signature in the presence of two witnesses.

JAMES R. MOFFATT.
